UNITED STATES PATENT OFFICE

2,538,343

SOCKET WRENCH HEAD AND STAKING DEVICE

Marshall Van Winkle, Jr., Oceanport, N.J.

Application October 25, 1946, Serial No. 705,505

2 Claims. (Cl. 81—10)

1

This invention relates to a socket wrench, and particularly such a wrench in which is embodied a staking device for closing the upper threads of a nut into close engagement with the bolt threads while the nut is still engaged by the wrench.

Another object of the invention is to provide such a wrench for manual or automatic operation in which the locking force can be accurately determined and made uniform for any desired number of operations.

A further object is to provide a wrench of simple and durable construction in which the staking tool is removable and replaceable.

Another object consists in providing certain improvements in the form, construction, and arrangement of the several parts whereby the above named and other objects may effectively be attained.

A practical embodiment of the invention is shown in the accompanying drawings, in which

Fig. 1 represents a vertical section through the wrench and nut, in the position assumed when the nut has been screwed home on a bolt;

Fig. 2 represents a horizontal section on the line II—II of Fig. 1, looking in the direction of the arrows;

Fig. 3 represents a bottom plan view of the wrench;

Fig. 4 represents a top plan view of the staking tool;

Fig. 5 represents a side elevation of the staking tool;

Fig. 6 represents a bottom plan view of the staking tool;

Fig. 7 represents a vertical section, corresponding to Fig. 1, with the parts in the position assumed when staking force has been applied to the wrench to deform the top of the nut;

Fig. 8 represents a horizontal section on the line VIII—VIII of Fig. 7, looking in the direction of the arrows, and

Fig. 9 represents an enlarged detail vertical section through the nut and bolt when the staking action has been completed, parts being broken away.

Referring to the drawings, a socket wrench head 1 has a "double-hex" nut-engaging socket 2 and a square upper socket 3 for engagement with any suitable manual or automatic turning means, the squared end of the latter being shown at 4. Above the socket 2 the head is provided with a cylindrical recess 5, having a diameter no greater than the minimum diameter of the socket 2, and terminating upwardly in the shoulder 6,

2

The staking tool 7 is shown as an annular piece of steel having a height approximately equal to the height of the recess 5 and having around its lower end an annular ridge 8, formed by beveled inner and outer surfaces joined at a slightly rounded peak. The angle of the inner bevel may be from 30° to 60° from horizontal, and the outer bevel is preferably steeper, for instance 80°. The outer diameter of the tool 7 is such that it can be inserted through the socket 2 and will have a snug friction fit in the recess 5 with its upper end resting against the shoulder 6. The inner diameter of the tool 7 is slightly greater than the maximum diameter of any bolt on which the wrench may be used, so that a high bolt can pass through the tool as the latter screws down a nut.

In operation, the wrench head and staking tool are assembled as just described, the head 20 being mounted on a turning means, such as an automatic wrench driver with controllable torque, the wrench is applied to a nut 9 to be tightened on a bolt 10, and the driver is operated to screw the nut home against the work 25 piece 11. The socket 2 is of less depth than the nut, so that when the parts are in a position shown in Fig. 1, the application of a blow or series of blows axially of the wrench head will drive the ridge 8 into the top of the nut while the wrench head moves down correspondingly around the nut to the position shown in Fig. 7.

The depth of the depression 12 in the top of the nut, and the corresponding inward displacement of the adjacent metal, can be regulated 35 accurately by an experienced operator, or by the adjustment of automatic hammering means in connection with the driving tool. Since the staking tool is, in effect, an integral part of the wrench head, it is always accurately located on the top of the nut, and the nut may be spun on freely and then staked to lock it firmly against accidental displacement.

The wrench shown herein is particularly useful in the application of slotted-head nuts of the types shown in Place Patent No. 1,734,445 and in Van Winkle Patent No. 2,431,627 (the latter type being shown in the drawings). In these nuts the upper part is divided into segments which are thrown inward to grip the bolt threads due to a cantilever action in the nut when it is screwed home. When the tops of such nuts are staked by the present tool the locking effect can be greatly increased without increasing the torque, but the segments have sufficient resilience

to permit removal of the nut when necessary without damage to the bolt.

The staking tool 7 is shown in connection with a "double-hex" wrench which is now most commonly used on assembly lines, but the tool is equally adaptable to "single hex" wrenches, by a suitable reduction of the outer diameter of the tool, if necessary, for ready installation and removal.

It is known that nuts have heretofore been staked or similarly deformed during manufacture and that the depressions in their upper surfaces have been of various shapes, either continuous (annular) or discontinuous. The ridge 8 shown herein is believed to be a preferable form for most purposes, but the provision of an annular row of more or less separated projections, of arcuate or other shapes, is intended to be included in the term "projecting element."

A socket wrench having points of similarity to that disclosed herein but designed to effect staking of the end of a bolt or stud forms the subject matter of my concurrently filed application, Serial No. 705,506, now issued as Patent No. 2,525,386.

It will be understood that various changes may be resorted to in the form, construction and arrangement of the several parts without departing from the spirit and scope of my invention, and hence I do not intend to be limited to the details herein shown and described, except as they may be included in the claims.

What I claim is:

1. A socket wrench head comprising, a lower socket adapted to surround and engage the sides of a nut, an upper socket adapted to engage the

end of a driving device, a cylindrical recess communicating with said lower socket and having a diameter equal to or slightly smaller than the minor diameter of the socket, said recess terminating inwardly at an annular shoulder, and a hollow cylindrical staking tool fitted in said recess with its upper end bearing against said shoulder, said tool having a co-axial annular ridge projecting from one end, the diameter of the tool being no greater than the diameter across the flats of a nut on which the tool is to be used, and the diameter of the bore being greater than the maximum diameter of a bolt on which said nut is to be screwed.

2. A tool according to claim 1 in which the annular ridge lies closer to the bore than to the outer surface of the tool.

MARSHALL VAN WINKLE, JR.
